GRID CATHODE ASSEMBLY FOR CATHODE-RAY TUBES

Wilson J. Tolson, Lancaster, Pa., assignor to Radio Corporation of America, a corporation of Delaware

Application October 30, 1946, Serial No. 706,700

12 Claims. (Cl. 250—27.5)

1

My invention relates to cathode ray tubes, and in particular to a cathode grid unit assembly for such tubes.

In a conventional type of cathode ray tube a cathode emitting electrode is axially aligned with the apertures in a plurality of plates or grids. In the type of cathode ray tube of which this invention is an improvement, electron emission from the cathode passes in turn through a control grid plate, a focusing grid plate, a first anode accelerating cylinder and a second anode grid plate. The spacing between the emitting surface of the cathode and the control grid is very critical.

In the past, spacers have been used to hold the cathode emitting surface at a predetermined distance from the control grid. These spacers have taken the form of metal eyelets and annular ceramic insulators, or the like. There are several objections to the use of spacers. Where several tube types are produced each requiring a different cathode-grid spacing, it is necessary to stock a large number of different size spacers. Also, as the cathode-grid distance is critical the spacer must closely conform by a small tolerance to the predetermined distance. This requirement necessitates precise work and close inspection for each metal or ceramic spacer.

Conventionally, the cathode tube or sleeve is coaxially supported by an annular ceramic disc mounted within the grid cylinder. Change in grid-cathode spacing is due to the expanding of the hot cathode sleeve when the heater is turned on. This is due to the metal of the cathode sleeve pushing away from the ceramic disc toward the grid aperture.

Also, in a conventional type of electron gun for cathode ray tubes, the cathode is open at the lower end to provide a passage for filament leads extending upward from the tube stem. This arrangement permits light from the filament to shine through the open end of the cathode upon the upper surface of the glass stem. This light is reflected from the surface of the glass stem forward into the tube envelope. Part of the reflected light falls upon the fluorescent target of the tube and tends to mask the signal. This result is particularly undesirable, for example, in aircraft radar receivers using cathode ray tubes in which faint signals would be hidden by the reflected light.

It is, therefore, an object of my invention to provide a cathode ray tube having an improved electrode construction.

Another object of my invention is to provide a

2

grid-cathode construction having accurate grid-cathode spacing.

It is also an object of my invention to provide a grid-cathode unit having a novel construction resulting in cheaper, quicker and a simplified assembly.

It is also an object of my invention to provide a grid-cathode unit construction which is assembled of parts made to greater tolerances, yet with a cathode to grid spacing conforming more closely to a predetermined distance.

It is also an object of my invention to provide a grid-cathode assembly which prevents the transmission of filament light.

15 It is also an object of my invention to provide a novel cathode-grid assembly which shortens the overall length of the electron gun.

The novel features which I believe to be characteristic of my invention are set forth with particularity in the appended claims, but the invention itself will best be understood by reference to the following description taken in connection with the accompanying drawing, in which:

Fig. 1 is an elevational view partly in section of a cathode ray tube incorporating the cathode construction according to my invention;

Fig. 2 is an elevational view in section of a cathode assembly according to my invention; and

Fig. 3 is an exploded elevational view in section of a cathode-assembly according to a modification of my invention.

My invention is directed principally to improvements in a cathode grid-assembly for use in a cathode ray tube. Such a cathode ray tube is disclosed in Fig. 1 as having an envelope 10 closed at one end by a glass stem portion 26 hermetically sealed to the sides of the envelope 10. Mounted upon the glass stem 26 is an electron beam-forming structure supported principally by ceramic side rods 11. Mounted on the side rods 11 and fixed relatively thereto is a cathode-grid assembly 12 for providing a source of an electron beam which is focused through a second grid structure 14 axially spaced along the tube from the cathode-grid assembly. Spaced in turn from the second grid 14 along the axis of the tube are a first anode 16, a second anode 18 and pairs of deflecting plates 20 and 22. These several structures form, focus and accelerate the electron beam in a manner well known in the art to strike the fluorescent screen 24.

The cathode-grid assembly is disclosed in greater detail in Figs. 2 and 3. The assembly 12 comprises, first, a container portion of cylindrical

parts 40 and 42. The cylindrical parts are of

different dimensions and are coaxially joined together by an annular shoulder portion 44. The grid body 40—42 may be formed in any manner that is expedient such as machining or by drawing. The cylindrical part 40 having a smaller cross-sectional diameter is closed at one end by a plate portion 45 having an aperture 46 coaxial with the cylindrical part 40. The cylindrical part 42 is provided with an aperture or opening 43 in the side wall thereof as shown in Figs. 1 and 2.

Mounted within the cylindrical portions 40 and 42 is a cathode structure or assembly 49, comprising an outer supporting cylinder or tube 50 fixed to a support eyelet or tube 56. The support eyelet 55 is flanged at its lower end to provide an outwardly projecting part 58. Welded to the outer surface of the support eyelet or tube 56 is an annular shield 60. A supporting ceramic spacer disc or annular plate 62 is mounted over the support eyelet or tube 56 and rigidly held between the flanged portion 58 and the annular shield ring 60. The outer support cylinder 50 is made of very thin metal foil preferably of a nickel-iron-cobalt alloy which has a low heat conductivity. Covering the upper portion of the supporting cylinder or tube 50 is a cathode cap 52 fixed at its edges to the support cylinder 50. The top portion of the cap 52 may be covered with an electron emitting material as is well known in the art. Fixed to the inner portion of the support cylinder or tube 50 is an inner cathode eyelet or tube 54 supported at its top end and extending downwards and coaxial with the cathode structure. The lower end of the inner cathode eyelet 54 is unsupported and spaced from the rest of the cathode structure.

The cathode assembly 49 is mounted within the grid body by securing the ceramic spacer 62 of the cathode structure between the shoulder portion 44 of the grid body and an end shield plate 68. Between the shield plate 68 and the ceramic washer 62 are placed two ceramic spacers or annular insulators 64 and 66. The annular shield 68 is fitted into the open end of the cylindrical portion 42 and forced against the ceramic insulators to a position where it is fixed by welding or brazing to the sides of the cylindrical portion 42. In this manner the cathode assembly 49 is rigidly mounted within the grid body 40—42, with the cap or tube portion 52 spaced from the apertured end plate 45.

Fig. 3 shows a modification of the grid body which comprises a single cylindrical portion or tube 76 closed at one end by a plate portion 78 having an aperture therethrough coaxial with the cylinder 76. At the open end of the cylinder 76 an aperture or opening 82 is formed through the side wall. Fixed within the cylinder 76 is an annular flanged ring 84 mounted by welding or brazing, for example, to the side wall of the cylinder 76 in a predetermined position. The annular ring 84 is provided with a flanged portion 86 against which abuts the supporting ceramic spacer 62 of the cathode assembly 49.

In Fig. 3 the cathode assembly 49 may be fixed within the grid body 76 in a manner similar to that shown in Fig. 2 in which the cathode assembly is locked by the plate 68. The cathode structure disclosed in Figs. 2 and 3 is of the indirectly heated type. In Fig. 2 is disclosed a filament 72 which may be of the double helical type extending inside the cathode assembly. The filament 72 is completely enclosed by the inner cathode eyelet or tube 54 and the cathode cap portion 52. The ends of the filament are brought down

through the apertured spacers 64 and 66 where they are mounted for support on two filament leads 74. Leads 74 extend into the grid body through the aperture 43 and between the ceramic spacers 64 and 66. They are frictionally held in position by the pressure exerted between the annular shield 68 and the shoulder 44 of the grid body. Filament leads 74 are of sufficient rigidity to be capable of supporting the filament 72. The cathode is furnished with an electrical lead 70 which also extends into the grid body through the opening 43. The lead 70 is frictionally held or pinched between the ceramic support 62 and the spacer 64. It is welded at 71 to the annular flange 58 of the cathode sleeve structure.

During tube operation, the incandescent filament 72 heats the cathode cap 52 to a temperature sufficient to cause electron emission from the activated coating on the surface of the cap. 20 During normal tube operation there is a sputtering of emissive material from the cathode cap onto adjacent portions of the cathode grid structure. To prevent shorting between the grid body 40 and the cathode 49, shield 60 extends out over 25 the ceramic supporting insulator 62. As shown in Figures 2 and 3, the peripheral portions of shield 60 are spaced from the upper surface of the insulator 62. This prevents any of the sputtered material from being deposited upon the 30 ceramic 62 and thus prevents the formation of an electrical path between the grid body 40 and the cathode assembly 49.

In cathode ray tubes of this type, the spacing between the cathode emitting surface and the 35 first grid is very critical. The amount of the spacing is usually very small, varying in different tubes all the way from 5 mils to 20 mils. Furthermore, the tolerance allowed for this spacing is usually 1 to 2 mils either way. To conform to 40 such close tolerance and to maintain the required spacing has proved very difficult. The problems of manufacturing are multiplied when these grid-cathode assemblies are made in large amounts. Previously, construction of the cathode grid assembly has required accurately formed elements whose dimensions vary, if any, by a very little. Furthermore, during the assembling of the cathode grid structure close inspection must be continually made to check any variation in structure 45 of one assembly from another.

In my invention, however, I have devised an arrangement of parts from which many of the difficulties of the past have been eliminated.

Fig. 3 shows several sub-assemblies, the grid body 76, the cathode sleeve unit 55 and the cathode support assembly 59. To assemble these several sub-assemblies so as to provide an accurate spacing between the cathode cap 52 and the apertured grid plate 78 the following procedure 50 may be used.

The cathode support assembly 59 is held by an appropriate jig mechanism (not shown). The cathode sleeve unit 55 is slipped over the support assembly 59 so that support cylinder 59 telescopingly fits over the support eyelet 56. The spacer 64 is next fitted on the top of cap 52. The grid body 76 is placed over these assembled units so that the lower open end of the grid body 76 slips down over the ceramic spacer 62. A suitable press means (not shown) forces the grid body 76 and the support assembly 59 together until the ceramic 62 abuts against the flange 86. The grid body 76 and assembly 59 are held in this position while a plunger means within the 60 jig is moved up through support eyelet or tube

56 and cathode eyelet or tube 54 to contact the inner surface of cap 52. The motion of the plunger is continued to carry the cathode assembly upward until the spacer 94 abuts against the inner surface of the grid plate 78. The cathode emitting surface 52 is now accurately spaced from the grid plate 78, while the grid unit 55 and the support assembly 59 are accurately positioned with relation to each other. Means are provided to lock the sub-assemblies 55 and 59 together in this relationship, while the grid body 76 is removed, then tubular sleeves 50 and 56 are welded together and spacer 94 removed from the cap 52.

With the two portions 55 and 59 of the cathode structure now welded together in the desired relationship the cathode-grid unit 12 may be assembled by any desirable means. The cathode assembly 55-59, without spacer 94, is inserted into the grid body 76. The two ceramic spacers 64 and 66 are inserted in turn. Leads 74 are positioned between spacers 64, 66 and filament 72 is then mounted within sleeve 54 on the ends of leads 74. The cathode assembly 55-59 and the spacers then are locked within the grid body 76 with the welding of the shield plate 68 to the wall of the grid body 76. This is done in such a manner that the ceramic spacers 62, 64 and 66 are held under pressure between the shield ring 68 and the flanged ring 84.

The advantages of this particular method of assembling the cathode grid structure are many. In the conventional type of cathode structure the cathode comprises of a simple cylinder supported by an annular ceramic disc which is fixed to the cathode cylinder between two flanged portions thereof. This cathode cylinder is spaced by a metal or a ceramic spacing means from the grid aperture. One common form of spacer is that of a metal eyelet between the apertured end plate of the grid body and the ceramic spacer.

In a conventional grid cathode assembly of this type the spacing between the cathode surface and the apertured grid plate is governed by the axial dimensions of the ceramic or metal spacer between the cathode unit and the grid plate. This part must be made to a predetermined axial dimension and within very small tolerances. Great difficulty has been experienced in providing support ceramics and spacer eyelets of the required axial dimension. Such difficulties are those of time consumed in checking and inspecting the component parts to determine whether they conform to the required dimensions. Such a procedure of cathode grid assembly has proved rather wasteful due to the discarding of many parts which do not come up to the exact standards required. Another difficulty has been in the making of several cathode grid structures in each of which there is a different cathode to grid spacing. In such cases it is necessary to stock spacer eyelets or ceramics of different sizes.

In the particular structure of my cathode and the method of assembly disclosed above, many of these difficulties do not appear or are eliminated. All that is required to make grid cathode assemblies having different spacings is the provision of a plurality of spacers one for each of grid-to-cathode spacing required. Furthermore, it is easily seen that with my particular cathode structure the axial dimension of the several component parts does not have to be critical. That is, the spacing between the cathode surface and the grid plate does not depend upon an accurate determination of the axial dimensions of any of

the cathode parts. The spacing is determined entirely by the spacer 94 and the parts are so designed that any reasonable variation in the axial dimension of any of the essential parts such as support ceramic 62, the support cylinder or tube 56 or the outer support cylinder or tube 50 will not affect the grid-cathode spacing. Furthermore, time consuming inspection of parts is eliminated.

10 A cathode grid assembly as disclosed in Figs. 1 and 2 has several other distinct advantages. In cathode ray tubes it is desirable to have the overall length of the tube as short as possible for reasons of installation. My particular cathode grid structure allows the mounting of the cathode gun structure closer to the glass stem of the tube. This is provided by the fact that the filament leads 74 and the cathode lead 70 pass through the side of the grid body. This arrangement is in contrast to the conventional method in which the cathode grid body is completely open at the lower end and the filament leads and cathode leads extend out through this open end. My arrangement allows the cathode grid structure to be supported closer to the tube stem 26.

20 Another great disadvantage of the conventional cathode grid assembly is that the open end of the grid assembly permits light from the filament to shine down upon the glass surface of the tube stem. This filament light is reflected from the surface of the glass stem forward upon the fluorescent screen at the opposite end of the tube. The phosphor of the screen glows from this reflected light and tends to mask or hide signals 30 produced on the fluorescent screen by the electron beam. This phenomenon has provided somewhat of a problem in aircraft radar kinescopes. In radar work many faint signals are picked up and these signals are completely hidden by the 35 glow due to the reflected light. To eliminate this particular difficulty I have completely closed off the bottom end of my cathode grid structure with the plate 68. This provides a grid body which 40 completely encloses a cathode structure in such a way as to screen any incandescent part of the 45 cathode assembly.

The particular structure of the cathode components described in Figs. 2 and 3 possesses still another advantage. To maintain the cathode 50 to grid spacing during normal tube operation has oftentimes proved to be a problem. In the conventional type of cathode structure described above, the high temperatures which the cathode structures attain cause an expansion of the cathode sleeve and if spacers are used between the cathode and the grid end plate these high temperatures cause a change in the dimensions of the spacers and a tendency for the end plate 55 on the cathode structure to warp. This last problem 60 has been eliminated in my structure with the elimination of the spacer elements.

In my cathode, the radiated heat from the filament is absorbed by sleeve 54 and conducted to the cathode cap 52 by this sleeve or inner cathode 65 eyelet 54. Furthermore, the cylinder 59 being of a very thin metal foil and also being of a low heat conducting alloy prevents escape of heat from the cap 52 to other parts of the cathode structure. If any axial expansion of the cathode 70 takes place it will mostly be in the highly heated inner eyelet 54. Since the lower end of this eyelet is unsupported all expansion will take place in a downward direction so that the cathode to grid spacing is maintained.

75 While certain specific embodiments have been

illustrated and described, it will be understood that various changes and modifications may be made therein without departing from the spirit and scope of the invention.

What I claim as new is:

1. A cathode electrode unit comprising a tube, means closing one end of said tube, means including a shield fixed to and projecting laterally from the surface of said tube, and a support member mounted on said tube and fixed in position between said shield and another of said projecting means, the peripheral portion of said shield being spaced from the surface of said supporting member.

2. A cathode electrode unit comprising a tube, means closing one end of said tube, means including a shield fixed to and projecting laterally from the surface of said tube, and an annular insulator member coaxially mounted on said tube and fixed in position between said shield and another of said projecting means, the peripheral portion of said shield being spaced from the surface of said insulating member.

3. A cathode electrode unit comprising a hollow tube, means closing one end of said tube, the other end of said tube having a flange portion extending outwardly therefrom, a support mounted with one surface in abutment against said flange portion, a shield means fixedly mounted on said tube in contact with an opposite surface of said support, whereby said insulator support is locked to said tube between said flange portion and said shield means.

4. A cathode electrode unit comprising a hollow tube, means closing one end of said tube, the other end of said tube having a flange portion extending outwardly therefrom, an insulator coaxially mounted with one face in abutment against said flange portion, and an annular shield fixedly mounted on the outer surface of said tube in contact with an opposite face of said insulator, whereby said insulator is locked to said tube between said flange portion and said annular shield.

5. A cathode electrode comprising a tube, means including an electron emitter surface closing one end of said tube, the other end of said tube having a portion extending outwardly therefrom, a shield mounted on the outer surface of said tube and spaced from said outwardly extending portion, an insulating spacer member mounted on said other end of said tube and held in fixed relationship by said outwardly extending portion and said shield.

6. A cathode electrode comprising a hollow tubular portion, means including an electron emitting surface closing one end of said hollow tubular portion, the other end of said tubular portion having an annular flange extending coaxially outwardly therefrom, an annular metal shield coaxially mounted on the outer surface of said other end of said tubular portion and spaced from said annular flange, an annular insulating spacer member coaxially mounted around said other end of said tubular portion and held in fixed relationship by said flange and said annular shield.

7. A cathode grid assembly unit comprising a grid body having two cylindrical wall portions of different diameters coaxially joined end to end by an annular wall portion, said annular wall portion partially closing said end of the larger cylindrical portion, a wall having an aperture at its center closing the other end of the smaller cylindrical portion, a shielding plate fixed to the inner

wall of said larger cylindrical portion and closing the other end thereof, an insulating support member clamped between said annular wall portion and said shielding plate, a cathode tube fixedly mounted at one end to said insulating support member, the other end of said cathode tube extending coaxially into said smaller cylindrical portion and having an electron emitting surface spaced from said apertured wall.

5 8. A cathode grid assembly unit comprising a grid body having two cylindrical wall portions respectively of different diameters coaxially joined end to end by an annular wall portion, said annular wall portion partially closing said end of the larger cylindrical portion, a wall having an aperture at its center closing the other end of the smaller cylindrical portion, a shielding plate fixed to the inner wall of said larger cylindrical portion and closing the other end thereof, said larger cylindrical portion having an aperture in the side wall thereof, an insulating support member and an annular spacer disc clamped side by side between said annular wall portion and said shielding plate, a cathode tube fixedly mounted at one end to said insulating support member, the other end of said cathode tube extending coaxially into said smaller cylindrical portion and having an electron emitting surface spaced from said apertured wall, a cathode lead fixed to said cathode tube and extending between said insulating support member and said spacer disc through said aperture in the side wall.

20 9. A cathode grid assembly unit comprising a grid body including two hollow cylindrical portions of different inside diameters, an annular portion coaxially joining said cylindrical portions together end to end, a wall portion closing the other end of said smaller cylindrical portion and having an aperture coaxially thereto, said larger cylindrical portion having an aperture in the cylindrical wall thereof, a cathode electrode unit including an electron emitting tube having an electron emitting surface at one end thereof and an annular insulating support fixedly mounted coaxially on said emitting tube at its other end, said cathode electrode unit mounted with the electron emitting surface of said tube extending coaxially into said smaller cylindrical portion in spaced relationship to said apertured wall and said annular insulating support in abutment with said annular portion, a pair of annular insulating spacer discs coaxially positioned side by side against said insulating support, and a circular plate shield closing the other end of said larger cylinder and fixed to said larger cylinder, said annular insulating support and said pair of spacer discs clamped together between said plate shield and said annular portion, a cathode electrode lead fixed to said cathode tube and extending through said aperture in the cylindrical wall of said larger cylinder, a pair of spaced cathode filament leads held between said pair of insulating spacers with one end of said filament leads extending into the apertured center of said insulating spacers, a cathode filament mounted on said one end of said filament leads and extending into said cathode tube, the other end of said filament leads extending through said aperture in the wall of said larger cylindrical portion.

25 10. A cathode grid assembly unit comprising a grid body having two cylindrical wall portions of different diameters and an annular wall portion joining said cylindrical wall portions, a shielding plate fixed to the inner wall of the

larger cylindrical portion and closing one end thereof, an insulating support member clamped between said annular wall portion and said shielding plate, a cathode tube fixedly mounted at one end to said insulating support member, the other end of said cathode tube extending coaxially into said smaller cylindrical portion.

11. A cathode grid assembly unit comprising a grid body including a hollow tubular member, stop means projecting from the inner surface of said tubular member, a tubular cathode electrode unit having an electron emitting surface at one end thereof, an insulator fixedly mounted on said tubular cathode unit at its other end, said cathode electrode unit mounted with the electron emitting surface extending into said tubular member with said insulator in abutment with said stop means, means closing the other end of said tube, said insulator clamped between said closing means and said stop means.

12. A cathode grid assembly unit comprising a grid body including a hollow tubular member, stop means projecting from the inner surface of said tubular member, said tubular member hav-

ing an aperture in the wall thereof, a tubular cathode electrode unit having an electron emitting surface at one end thereof, an insulator fixedly mounted on said tubular cathode unit at its other end, said cathode electrode unit mounted with the electron emitting surface extending into said tubular member with said insulator in abutment with said stop means, means closing the other end of said tube, said insulator clamped between said closing means and said stop means, a cathode electrode lead fixed to said cathode electrode and extending through said aperture in the wall of said tube.
